UNITED STATES PATENT OFFICE.

DONALD M. McALPIN, OF SAVANNAH, GEORGIA.

PLOW.

SPECIFICATION forming part of Letters Patent No. 308,682, dated December 2, 1884.

Application filed April 23, 1884. (No model.)

To all whom it may concern:

Be it known that I, DONALD MELROSE McALPIN, of Savannah, in the county of Chat-
ham and State of Georgia, have invented a new
5 and useful Improvement in Plows, of which
the following is a full, clear, and exact de-
scription.

Reference is to be had to the accompanying
drawings, forming a part of this specification,
10 in which similar letters of reference indicate
corresponding parts in all the figures.

Figure 1 is a side elevation of a plow to
which my improvement has been applied.
Fig. 2 is a plan view of the same. Fig. 3 is a
15 sectional end elevation of the beam and draw-
plate, taken through the line *xx*, Fig. 1. Fig.
4 is a sectional end elevation of the beam and
draw-plate, taken through the line *yy*, Fig. 1.
Fig. 5 is a view of the draw-plate.

20 The object of this invention is to promote
convenience and efficiency in the use of plows.

The invention consists in the combination,
with a short beam having perforations in its
lower forward part and provided with a **U**-
25 shaped bracket and its adjustable bolt, of a
clevis and a flat draw-plate, whereby a short
beam can be used and the draft attachment
can be readily adjusted as the character of
the soil may require.

30 A is the point, B the mold-board, C the
standard, and D the handles, of an ordinary
plow. E is the beam, which is secured at its
middle part to the standard C, and is con-
nected at its rear end with the handles D by
35 a rod, F. The beam E is made short, and to
its forward end is secured a **U**-shaped bracket,
G, with its arms projecting downward. The
bracket G is secured in place by a bolt, H,
which passes up through the beam E and
40 through the bend of the said bracket, as shown
in Fig. 4, and has a nut, I, screwed upon its
upper end. Several holes are formed through
the arms of the bracket G, to receive the bolt
J, so that the said bolt can be adjusted higher
45 or lower, as may be desired.

In the lower part of the beam E, in front of
the standard C, is formed a number of holes,
K, to receive the bolt L of the clevis M, which
hangs below the beam E, and the bend of which
passes through an eye formed in the rear end 50
of the draw-plate N. The plate N is made
about ten inches long, four inches wide, and
a quarter of an inch thick, and has an eye at
each end. The draw-plate N passes between
the arms of the bracket G, and is kept in 55
proper position by the bolt J of the said
bracket. The draft is applied to the eye at
the forward end of the draw-plate N. With
this construction, by moving the clevis M to
the rearward and raising the forward end of 60
the draw-plate N by adjusting the bolt J, the
plow can be made to "take" in any kind of
soil. By moving the clevis M forward and
lowering the forward part of the draw-plate
N by moving the bolt J downward, the plow 65
will be caused to make a lighter cut, so that
the plow can be readily adjusted as the char-
acter of the soil may require. With this con-
struction, also, the employment of a short
beam is made practicable, the plate N hold- 70
ing the plow steady, so that the point of draft
attachment can be brought near the plow, and
the draft of the said plow thus made lighter.

Having thus described my invention, I claim
as new and desire to secure by Letters Patent— 75

The combination, with the short beam E,
having perforations K, and provided with the
U-shaped bracket G, and bolt J, of the clevis
L M and the flat draw-plate N, substantially
as herein shown and described, whereby a 80
short-beam plow can be used and can be
readily adjusted as the character of the soil
may require, as set forth.

DONALD M. McALPIN.
